UNITED STATES PATENT OFFICE.

SAMUEL DUNCAN BLACK AND ALONZO GALLOWAY DECKER, OF BALTIMORE, MARYLAND, ASSIGNORS, BY MESNE ASSIGNMENTS, TO THE MARYLAND TRUST COMPANY, TRUSTEE, A CORPORATION OF MARYLAND.

ELECTRICALLY-DRIVEN TOOL.

Application filed June 14, 1920. Serial No. 388,746.

To all whom it may concern:

Be it known that we, SAMUEL DUNCAN BLACK and ALONZO GALLOWAY DECKER, citizens of the United States of America, 5 and residents of Baltimore County, State of Maryland, have invented certain new and useful Improvements in Electrically-Driven Tools, of which the following is a specification.

10 This invention relates to an improved, electrically driven tool, of the type described in United States Patent No. 1,245,860, and particularly to the controlling device or switch which is a feature of 15 that patent. A difficulty with that type of switch, i. e., the rotary switch, was that incident to maintaining a uniform and sufficiently close contact between the rotary contact block and the switch arm or leaves. 20 Bending or loss of tension in one of the spring leaves would cause the contact of that leaf with the block to become imperfect, resulting in arcing and consequent deterioration of the contact by burning. As 25 already suggested, this loss of tension in the spring leaves is apt to be more pronounced in one member than in the other and conversely it was difficult to adjust the two spring leaves to get equal tension and equal 30 closeness of contact on both sides of the block. This difficulty has been overcome in the present instance by mounting the spring arms or leaves of the switch on a support which is pivoted to swing freely, permitting 35 the spring arms to adjust themselves, equalizing the contact pressure of the two arms on the respective sides of the rotary contact block.

Another feature of the invention is found 40 in the construction of the switch whereby the rotary contact block may, when burnt out, be conveniently removed and replaced without necessitating the employment of special tools.

45 The invention further resides in the arrangement of the details of the contact block in such a manner as to give increased economy in production and efficiency of operation.

50 In the accompanying drawings we have illustrated an electrically driven tool and parts thereof, embodying the features of our invention in its preferred form.

In the drawings:

Figure 1 is a sectional elevation of the 55 switch-box and grip of the electric tool of the invention, the plane of section being parallel to the axis of the tool.

Figure 2 is a section on the line 2—2 of Figure 1, at right angles to the plane of 60 Figure 1 and on the axis of the contact block.

Figure 3 is a section on the line 3—3 of Figure 2, illustrating the details of the 65 contact block.

Figure 4 is a plan of the switch-box.

Figure 5 is an elevation of the tool.

Referring to the drawings by numerals, each of which is used to indicate the same or similar parts in the different figures; the 70 tool as indicated consists of a suitable frame or casing (1), in which is mounted an electric motor (2), with gearing or suitable connections (3), to a tool chuck (4). The tool is supported and guided by a 75 handle or pistol grip (5) and controlled by a switch (6) actuated by a trigger (7).

Having particular reference to Figures 1 to 4, illustrating the details of the switch to which the invention particularly relates, the 80 switch consists of a rotary contact block (10) and two spring contact arms (9 and 11) mounted on an insulating carrier block (12), to the opposite sides of which the contact arms (9 and 11) are secured by rivets 85 (13) or other suitable means. The contact arm (11) is connected to an insulated wire (14) leading from a source of electric current, and the contact arm (9) is similarly connected by a wire (15) to the motor (2). Connected to a screw and hook-like binding post (40), the wire 14 leads to a suitable source of electricity and the opposite contact arm carries a second similar binding post (41) from which a wire 15 leads to the 90 motor. The return or wire (17) leading from the motor is supported on the contact block by a screw or suitable attachment (42). The return, ground, or negative connection 95 (17) is joined to the opposite terminal of the motor so that when the two switch arms (9 and 11) are closed or electrically connected to the contact block (10) the motor is in circuit, and when they are disconnected by rotation of the block to a position in which they engage the non-conducting portions of

100
105

the block, the motor is thrown out of circuit and becomes inoperative.

The contact block (10), in accordance with the regular practice, is of substantially 5 square cross-section, as seen in Figure 3, which is taken at right angles to the axis, and has two opposite, non-conducting faces (45—45) and two likewise opposite, electrically-conducting faces (16—16), which 10 are electrically connected to each other. In the present instance these electrically-conducting faces (16—16) and the connecting means therefor, indicated by reference character (46) are formed and consist of a U-shaped strap of metal, clasping and enclosing 15 the hard rubber block (18) which forms the body of the contact block, the two legs of the U forming the conducting, contacting surfaces (16—16) and the cross-arm of 20 the U forming the connection (46) which is led across one of the axial ends of the block (18) and preferably seated in a suitable groove or depression therein.

Preferably the block 10 is cut away at 25 47 below the edges of the contacting surfaces (16—16) to prevent arcing at this point when the terminals are disconnected.

In the form of the invention shown the rubber is cut away to form an insulating 30 hub portion (19) concentric with the axis at the end of the block occupied by the cross-arm of the U, and the cross-arm is apertured to admit the hub which is also passed through an insulating washer (20) completely separating and insulating the 35 contacting portions (16 and 46) of the contact block from the metallic casing or box (1) in which it is mounted.

The manner of mounting the contact block 40 in the casing is an important structural detail lending to economy of production and particularly to convenience in replacing the contact members if burned or otherwise destroyed. The casing is provided with two 45 abutments (21 and 22). The frame (22) on one side is pierced by a small aperture (24) of circular cross-section and of the diameter of the small end of the shaft (23) as hereinafter described. The opposite side 50 (22) is pierced, in alignment with this aperture (24), with an aperture (25) of considerably greater diameter, and this aperture is enlarged adjacent the outer surface of the box or casing, forming a counter-sink (26). 55 The shaft (27) of the carrier block (10) is mounted in these aligned openings or apertures (24 and 25). This shaft is of square or angular cross-section as to its intermediate portion (28), so as to provide a non-rotating 60 connection with the block (10), which is mounted on and has a square or angular aperture to fit the shaft. A ratchet (29), which is likewise provided with a square, central, axial aperture, is mounted on the 65 same shaft side of the contact block. The

ends of the shaft (23 and 30) are round, to give a rotary engagement with the corresponding openings (24 and 25), and the small end (23) of the shaft extends outward beyond the surface of the casing and is provided with a cotter-pin (31), to prevent accidental withdrawal of the shaft. The opposite end of the shaft is enlarged at 30 to fit the enlarged opening (25), and provided with a head (32), engaging and seated in the counter-sink (26). On the form shown the enlarged end (30) is marked with an arrow or pointer (50), which in conjunction with suitable markings on the frame indicates the "on and off" position of the switch. 70 The rotary parts (10 and 29) need not be otherwise fastened to the shaft, i. e., by pinning or keying, but are merely slipped over the shaft, so that if it becomes necessary to replace these members, to remove them the operator has only to withdraw the cotter-pin (31) and slip out the shaft by pressing on the protruding end, causing the head to project, when it may be withdrawn releasing the contact block and ratchet, making 75 the replacement of the contact block when necessary a simple operation requiring no special tools and occupying only two or three minutes' time.

In the preferred form the wires or cable 80 leading to the source of electricity are introduced thru a covered aperture or split. The boss (51), the upper half or cover (52) of which is removable for convenience in introducing the cable. It is held by screws 85 (53) by which the cable is clamped. This clamping prevents straining or pulling loose of the connections.

As already pointed out, some difficulty has 90 been encountered in connection with such switches, owing to the unevenness of contact of the arms (9 and 11) with the block (10) due to one or both of the arms being more or less bent out of position and the difficulty 95 of giving them equal tension. In the present instance we have succeeded in equalizing the pressure of these arms by pivoting the insulating carrier (12) on which they are mounted, so that it swings freely about a suitable shaft (33). Under these circumstances 100 it is only necessary to arrange the spring arms so that they are spaced at their ends by a distance somewhat less than the dimension of the contact block, and the pivotal mounting of the carrier equalizes the 105 tension. In case the closeness of contact becomes insufficient it is only necessary to bend the arms together, when the equalizing effect takes care of the question of individual adjustment.

To rotate the contact block step by step to on and off position, we have provided a trigger lever (34), as in the aforementioned patent, the lever being pivoted in the frame or casing at 110 and extending well upward 130

to the level of the ratchet (29). This trigger lever carries pivoted at its upper end a pawl (36), and both the pawl and the trigger are controlled by a spring (37). When the trigger is pressed the pawl engages a tooth of the ratchet (29) and rotates the ratchet substantially a quarter of a revolution, carrying the contact block through a similar arc, the pressure of the spring contacts arms on the square faces of the block, which are shown preferably at 90° to each other, completing the 90° rotation. The fibre block (12) acts as a stop for the trigger and pawls to prevent the escape of the pawls to an inoperative position.

Presuming that the block has been turned into contacting position, the trigger having been withdrawn by the spring, it is turned into off position by a second pressure on the trigger, engaging the next tooth and turning the block through a second arc of approximately 90°.

We have thus described an electrically driven tool and the controlling means therefor, embodying our invention in its preferred form, specifically and in detail, in order that the nature and operation of the invention may be clearly understood to those skilled in the art; however, the specific terms herein are used descriptively rather than in a limiting sense, the scope of the invention being defined in the claims.

What we claim and desire to secure by Letters Patent is:

35. 1. In an electrically driven tool means for starting and stopping the tool comprising a rotary switch-block; spring-controlled contact arms engaging opposite faces of the block; and a pivotally mounted insulating carrier for said arms.
40. 2. In an electrically driven tool means for starting and stopping the tool comprising a rotary contact block, having a plurality of conducting faces and means electrically connecting the same; spring contact arms adapted to engage said conducting faces in the closed position of the contact block; and a non-conducting carrier for said arms, the carrier being pivotally mounted to equalize the contact pressure of the arms.
45. 3. In a portable, electrically driven tool

means for starting and stopping the tool comprising a rotary contact block, having a plurality of conducting contact faces with means electrically connecting the same; a 55 trigger-like lever and means whereby the trigger lever rotates the contact block step by step as it is pressed and released; spring-actuated contact arms engaging said contact faces in the closed position of the contact block; and a pivotally mounted, non-conducting carrier for said contact arms whereby the contact pressure is equalized.

4. A switch for an electrically driven tool, consisting of a rotary block of insulating material having opposite, conducting, contacting surfaces and a ratchet member, both having axial openings of angular cross-section; a switch-box having opposite bearings, one of said bearings being enlarged; a shaft 70 having an enlarged journal to fit said enlarged bearing; a portion of angular cross-section to fit the opening in the block and ratchet; and a smaller journal portion to fit the opposite bearing, the shaft being of such 75 length as to provide a projecting end which is transversely apertured to receive a pin, to prevent withdrawal of the shaft.

5. In an electrically driven tool means for starting and stopping the tool comprising 80 a rotary switch-block; spring-controlled contact arms engaging opposite faces of the block; an insulating carrier for said arms, and a trigger switch with a pawl engaging the contact block, the carrier acting as a stop 85 for the trigger and pawl.

6. In an electrically driven tool means for starting and stopping the tool comprising 90 a trigger switch mounted on a pivot pin seated in the body of the tool frame; a shaft to which the switch is secured; indicating means on the tool frame and co-operating means on the shaft end to indicate the on and off positions of the switch.

Signed by us at Towson, Maryland, this 95
